UNITED STATES PATENT OFFICE.

LAURENCE E. TOPHAM, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

CHAIN-STITCH INSEAM SHOE-SEWING MACHINE.

1,241,784.

Specification of Letters Patent.

Patented Oct. 2, 1917.

Application filed January 24, 1916. Serial No. 73,881.

To all whom it may concern:

Be it known that I, LAURENCE E. TOPHAM, a citizen of the United States, residing at Swampscott, in the county of Essex and 5 State of Massachusetts, have invented certain new and useful Improvements in Chain-Stitch Inseam Shoe-Sewing Machines; and I do hereby declare the following to be a full, clear, and exact description of the invention, such as will enable others skilled in 10 the art to which it appertains to make and use the same.

The present invention relates to chain stitch inseam shoe sewing machines which 15 employ a curved hooked needle and which are used to sew together the upper and insole of turned shoes or the welt, upper and insole of a welted shoe.

After the inseam of a shoe has been sewn 20 on a machine of the class above referred to, the last loop of thread drawn through the work by the needle must be freed from the needle hook or barb and the needle must be brought to rest out of engagement with the 25 work before the shoe can be removed from the machine. The object of the present invention is to provide novel and efficient means for performing these operations automatically as the machine is stopped so that 30 no additional manipulation of the machine by the operator is required and the shoe can be removed as soon as the sewing operation is completed.

With this object in view, the present invention contemplates the provision in a machine of the class referred to of means which 35 will act automatically as the machine is stopped to advance the needle from its retracted position, in which position the last 40 loop of needle thread is firmly seated in the barb of the needle, toward the work a sufficient distance to free the barb from the thread and bring the needle to rest in advanced position out of engagement with the 45 work and at a sufficient distance from the work so as not to interfere with the removal of the shoe. The thread ordinarily used in inseam shoe sewing machines is saturated with wax and it has been found in actual 50 practice that the loop of such a saturated thread is sufficiently rigid to free itself from the barb as the needle advances toward the work and that an advancing movement can be given to the needle sufficient to free the 55 thread from the barb without moving the

needle so far as to interfere with the removal of a sewed shoe from the machine. In inseam shoe sewing machines provided with a curved, hook needle or barb needle, the hook or barb is on the side of the needle 60 away from which the work is fed and by reason of this arrangement of the needle hook or barb, when the needle loop is freed from the barb of the needle during the advancing movement of the needle, the loop 65 either falls completely out of engagement with the needle or the end of the loop rests against the smooth side of the needle which is opposite to the side in which the barb is formed. There is no liability, therefore that 70 the needle loop will catch in the barb of the needle when the shoe is removed from the machine.

The present invention contemplates producing the advancing movement of the 75 needle from its retracted position in any desired manner. To secure this advancing movement and to cause the needle to be stopped with certainty in the desired advanced position out of engagement with the 80 work, the preferred form of the invention contemplates reversing the direction of rotation of the cam shaft of the machine as the machine is stopped, this reversal taking place substantially at the point in the cycle 85 of operations of the machine in which the needle is in retracted position.

Inseam shoe sewing machines of the class which comprise a curved hook needle are provided with guides for the work consisting, usually, when the machine is used for turned work, of a back gage and a back rest or bunter, and, when the machine is used for welted work, consisting of a back rest or bunter and a welt guide. During each 95 cycle of operations of the machine the back rest or bunter is locked and unlocked and the back gage or welt guide is locked and unlocked and is also moved toward and from the shoe. The timing of the locking and 100 actuating devices for the work guides of these machines is such that both guides are in contact with the work and locked during the retracting stroke of the needle. When, therefore, as in the preferred embodiment 105 of the present invention, a final advancing movement is given to the needle as the machine is stopped by the reversal in the direction of rotation of the driving shaft, the needle comes to rest at a point in the cycle 110

of operations in the machine in which both work guides are in contact with the work and locked against backward movement. To facilitate the removal of the shoe from the machine it is desirable that both work guides be unlocked and that the welt guide or back gage be retracted and, accordingly, features of the present invention contemplate the provision of means for unlocking these guides and retracting the back gage or welt guide as hereinafter described and claimed.

The several features of the present invention will be clearly understood from an inspection of the accompanying drawings in which the preferred embodiment of the invention is illustrated as applied to a welt shoe sewing machine of well known construction.

Referring to the drawings, Figure 1 is a view in side elevation of the complete machine; Fig. 2 is a view in side elevation partly in section of the head of the machine illustrating particularly the stitch forming and work guiding devices; Fig. 3 is a view in vertical section with some of the parts shown in elevation, of the head of the machine illustrating the mechanism by means of which an advancing movement from its retracted position is imparted to the needle as the machine is stopped and the needle is brought to rest in advanced position out of engagement with the work; Fig. 4 is a plan view partly in section of the mechanism illustrated in Fig. 3; Fig. 5 is a detail cross-sectional view taken on the line 5—5 of Fig. 4 looking in the direction of the arrows; Fig. 6 is a detail cross-sectional view of the head of the machine illustrating the brake and positive stop which are brought into operation during the reverse rotation of the cam shaft; Fig. 7 is a detail view in rear elevation of certain of the parts illustrated in Fig. 6; and Figs. 8 and 9 are somewhat diagrammatic detail views illustrating the action of the needle in freeing the thread from the needle barb when the machine is stopped, Fig. 8 illustrating the manner in which the needle loop is held in the barb of the needle when the needle is at the limit of its retracting stroke and Fig. 9 illustrating the manner in which the needle loop has been freed from the barb of the needle after the needle has been advanced and brought to rest in advanced position out of engagement with the work. In Fig. 8 for the sake of clearness the rear or work side of the needle loop is shown displaced somewhat from the position which it actually assumes when the needle is retracted.

The welt shoe sewing machine illustrated in the drawings, except as hereinafter described, is the same in the construction, arrangement and mode of operation of the parts as the machine disclosed in the patent to Eppler No. 1,108,560 dated August 25,

1914. Referring to Fig. 2 of the drawings, the curved hook needle of the machine is indicated at 1, the looper at 2, the thread arm at 3, the welt guide at 4, the welt guide slide at 5, the back rest or bunter at 6, the back rest slide at 7, the locking wedge for the welt guide and back rest slides at 8, the thread tension devices at 9, the cam shaft at 10 and the tension releasing link which is actuated by reversal in the direction of rotation of the cam shaft at 11. During the operation of the machine, the cam shaft 10 is driven continuously in the direction indicated by the arrow in Fig. 1 by means of a belt 12 passing over a pulley 13 on the cam shaft and over a pulley 14 secured to a shaft 15 mounted in the base of the machine. The shaft 15 is connected by beveled gears 16 and 17 to a sleeve mounted on the power shaft 18 of the machine and provided with one member 19 of a friction clutch. The other member 20 of the friction clutch is splined on the shaft 18 so as to rotate therewith and is acted upon by a spring 21, the tendency of which is to separate the clutch members. The clutch member 20 is arranged to be acted upon by a wedge 22 which is connected to a foot treadle 23 the arrangement being such that by means of the foot treadle 23 and wedge 22 the speed of the machine can be regulated and the machine can be disconnected from its driving power and allowed to stop by a total release of the treadle 23.

The machine illustrated in the drawings is provided with means whereby when the treadle 23 is released to stop the machine the needle is brought to its retracted position as indicated in Fig. 8 and is then advanced toward the work as indicated in Fig. 9 and 105 brought to rest in this advanced position out of engagement with the work. The result of this movement of the needle frees the last loop of needle thread from the barb of the needle, as indicated in Fig. 9 and leaves the 110 needle and thread in such condition that the shoe can be immediately removed from the machine without any further manipulation of the machine by the operator. As is clearly shown in Figs. 8 and 9 the barb of 115 the needle is on the side of the needle away from which the work is fed, or in other words, the barb of the needle faces the portion of the seam which has been completed. When the needle is in its retracted position, 120 as indicated in Fig. 8, the last loop of needle thread is held tightly in the barb of the needle, but when the needle advances and stops in the position indicated in Fig. 9 the needle loop is forced out of the barb and the 125 end of the loop is either completely free of the needle or rests lightly against the smooth side of the needle opposite the barb, as indicated in Fig. 9.

The mechanism illustrated in the draw- 130

ings for advancing the needle from its retracted position toward the work and bringing it to rest in advanced position out of engagement with the work is mounted in the head of the machine and acts upon the cam shaft 10. This mechanism includes a reversely driven friction clutch mounted on the cam shaft of the machine, which when thrown into operation, acts first as a friction 5 brake to slow down and stop the cam shaft, and then to rotate the cam shaft in a reverse direction. This mechanism also includes devices for throwing the friction clutch out of operation and for stopping the cam shaft 10 after it has been rotated to a predetermined 15 position. This mechanism also includes devices thrown into operation when the stopping treadle is released for throwing the friction clutch into operation at such a time 20 in the cycle of operations of the machine that the cam shaft of the machine will be reversed substantially at the time when the needle has completed its retracting stroke.

The friction clutch above referred to comprises a continuously reversely rotating clutch member 24 mounted loosely on the cam shaft 10 and a coöperating member 25 mounted to rotate with the cam shaft. The clutch member 24 is rigidly connected with 25 a worm gear 26 which is constantly driven by means of a worm 27, the shaft of which is provided with a pulley 28 driven through a belt 29 from a pulley 30 on the power shaft 18 of the machine. The clutch member 25 is provided with a hub 31 which is connected to rotate with the belt pulley 13 by means 35 of a block 32 projecting from the pulley between lugs 33 on the hub 31. This connection causes the clutch member 25 to rotate 40 with the cam shaft but permits a movement of the clutch member longitudinally of the cam shaft toward and from the clutch member 24. During the normal operation of the machine in sewing a seam the clutch member 25 is held out of engagement with the clutch member 24 by means of a spring 34. This spring is interposed between the head of a pin 35 and the bottom of a recess in the block 32. The pin 35 extends through 45 the block 32 and is provided on its inner end with a plate 36 overlapping the projections 33 from the hub 31 of the clutch member. To cause the clutch member 25 to be moved into and out of engagement with the clutch member 24 the hub 31 of the clutch member 25 is provided with a cam groove 37 which is engaged by a roll on one end of 50 a bell crank lever 38 pivotally mounted on the frame of the machine. The other end 55 of the bell crank lever is provided with a hole 39 adapted to receive a locking bolt 40 which while the machine is sewing a seam is held out of engagement with the bell crank lever so that the bell crank lever is 60 oscillated idly by the cam groove and the

clutch member 25 remains out of engagement with the clutch member 24. When, however, the treadle 23 is allowed to rise, the bolt 40 is permitted to engage the hole in the bell crank lever 38. The release of 70 the treadle 23 releases the driving clutch disks 19 and 20 so that the machine is disconnected from its driving power and at the time the bolt 40 engages the bell crank lever 38 the cam shaft 10 of the machine is 75 turning forward under momentum. The continued forward rotation of the cam shaft 10 causes the cam groove 37 to force the clutch member 25 into engagement with the clutch member 24, but inasmuch as these 80 members are rotating in opposite directions the cam shaft is first slowed down and stopped and then reversely rotated until the cam groove 37 acting on the roll in the arm of bell crank 38 moves the clutch member 85 25 out of engagement with the clutch member 24. The cam groove 37 in the hub of clutch member 25 is so shaped, and located in such an angular position on the cam shaft that the reversal in the direction of rotation 90 of the cam shaft takes place substantially at the time when the needle is at the limit of its retracting stroke, as indicated in Fig. 8 and the clutch member 25 is disconnected from the clutch member 24 just before the 95 needle reaches the position indicated in Fig. 9.

The locking pin 40 is mounted in the end of a slide 41 which is held in normal position by a spring 42. The spring surrounds a bolt 43 extending from the rear end of the slide and is interposed between a shoulder on the slide and the inner end of an adjustable screw threaded sleeve 44. The bolt 43 carries a nut 45 which engages the outer 100 end of the sleeve and holds the spring under tension. The locking bolt 40 is acted upon by a spring 46 which tends to raise it into engagement with the bell crank lever 38 and the bolt is provided with a latch 47 arranged to engage a shoulder 48 on the slide 41 and hold the bolt in its lower position until the treadle 23 has been raised sufficiently to allow the locking bolt to engage the bell crank lever. The latch 47 is loosely 110 pivoted on a rock shaft 49 journaled in a block secured to the lower end of the locking bolt 40 and is connected with the rock shaft by a pin 50 projecting through a slot in the hub of the latch. The rock shaft 49 115 is provided with an arm 50a which is connected by a rod 51 to the starting and stopping treadle 23. With this construction, when the treadle 23 is depressed the rock shaft 49 turns until the latch 47 brings up 120 against the slide 41 and then during the continued downward movement of the treadle the locking bolt is drawn down against the tension of its spring. This carries the latch 47 under the shoulder 48. When the treadle 130

is released the latch 47 prevents the upward movement of the locking bolt and the rock shaft 49 is rocked until the pin 50 strikes the end of the slot in the hub of the latch 5 and swings the latch outward, thus disengaging it from the shoulder 48. When this takes place the spring 46 forces the locking bolt upward against the under side of the bell crank lever 38 and when the hole in the 10 lever registers with the locking bolt the bolt snaps up into the hole 39, thus connecting the bell crank lever with the slide 41. When the bell crank lever 38 and the slide 41 are connected by the locking bolt the movement 15 of the bell crank lever is resisted by the spring 42 and the clutch members 25 and 24 are pressed together with a force depending upon the tension of the spring 42.

During the reverse rotation of the cam 20 shaft 10 the link 11 is actuated as in the patent hereinbefore referred to to release the tension on the thread. In the machine illustrated in the drawings the link 11 is also utilized to apply a brake to the cam shaft 25 and also throw into operation a positive stop. This brake and positive stop are best illustrated in Fig. 6. As shown, the brake consists of a brake band 52 arranged to act on a disk secured to the cam shaft. One end 30 of this brake band is secured to the frame of the machine and the other end is secured to an eccentric 53 formed on the stud 54 which forms the pivotal connection between the link 11 and the bell crank 55 which forms a 35 portion of the tension releasing mechanism. An endwise reciprocation of the link 11 which takes place upon a reversal in the direction of rotation of the cam shaft thus applies the brake band 52. To release the 40 brake band by the downward movement of the starting treadle so that the brake may be removed before the machine is started the stud 54 is provided with a slotted arm 56 which is engaged by the pin 57 which forms 45 the pivotal connection between the arm 50 and the rod 51. The positive stop consists of a finger 58 projecting from the hub of the bell crank 55 and adapted to be moved into the path of a shoulder 59 on a stop disk 50 secured to the cam shaft when the bell crank is rocked by the reciprocation of the link 11.

In the machine illustrated in the drawings the welt guide 4 and the back rest 6 are in engagement with the shoe when the needle 55 is in the position indicated in Fig. 9 and also at this time the locking wedge 8 is in its advanced position in which both slides 5 and 7 are locked. To permit the shoe to be removed after the machine has been stopped 60 with the needle in the position indicated in Fig. 9 the machine illustrated in the drawings is provided with means operated from the link 11 for unlocking both slides 5 and 7 and for retracting slide 5. This means, as 65 illustrated in Fig. 2, comprises a bell crank

lever 60, one arm of which is arranged to be depressed by a plunger 61 connected to the horizontal arm of the bell crank 55, the other arm of which is connected to the welt guide slide 5 and to the locking wedge 8. The connection between the bell crank 60 and the locking wedge 8 consists of a link 62 pivoted at one end to the vertical arm of the bell crank and at its other end passing through a lug projecting from the locking wedge and 70 provided with a nut 63 to engage the lug and retract the wedge whenever the bell crank 60 is actuated by a depression of the plunger 61. To connect the bell crank 60 with the welt guide slide 5 the upper end of 75 the vertical arm of the bell crank is provided with a hole through which a rod projecting from the rear end of the welt guide slide passes. This rod at its outer end is provided with a nut 64 with which the upper end of the bell crank 60 engages to retract 80 the welt guide slide. The position of the nuts 63 and 64 is such that the locking wedge 8 is actuated to unlock the welt guide slide before the nut 64 is engaged by the bell crank 90 to retract the slide.

The nature and scope of the present invention having been indicated and the preferred form of the invention having been described, what is claimed is;—

1. A chain stitch inseam shoe sewing machine, having in combination, stitch forming devices including a curved hooked needle and a looper, and means operating automatically on stopping the machine to advance the needle from its retracted position to free the hook from the last needle loop and bring the needle to rest in advanced position out of engagement with the work.

2. A chain stitch inseam shoe sewing machine, having in combination, stitch forming devices including a curved hooked needle and a looper, and means operating automatically on stopping the machine to reverse the direction of rotation of the cam 100 shaft of the machine to advance the needle from its retracted position so as to free the hook from the last needle loop and bring the needle to rest in advanced position out of engagement with the work.

3. A chain stitch inseam shoe sewing machine, having in combination, stitch forming devices including a curved hooked needle and a looper, a work guide, means operating automatically on stopping the machine to 120 advance the needle from its retracted position to free the barb from the last needle loop and bring the needle to rest in advanced position out of engagement with the work, and means thrown into operation on 125 stopping the machine for retracting the work guide.

4. A chain stitch inseam shoe sewing machine, having in combination, stitch forming devices including a curved hooked needle 130

and a looper, means operating automatically on stopping the machine to reverse the direction of rotation of the cam shaft of the machine to advance the needle from its retracted position so as to free the hook from the last needle loop and bring the needle to rest in advanced position out of engagement with the work, a work guide, means for locking and unlocking the work guide during each cycle of operations of the machine, and means thrown into operation on stopping the machine and operating during the reverse rotation of the cam shaft to unlock and retract the work guide.

15 5. A chain stitch inseam shoe sewing machine, having in combination, stitch forming devices including a curved hooked

needle and a looper, means operating automatically on stopping the machine to reverse the direction of rotation of the cam shaft of the machine to advance the needle from its retracted position so as to free the hook from the last needle loop and bring the needle to rest in advanced position out of engagement with the work, a work guide, a 20 work rest, means for locking and unlocking the work guide and work rest during each cycle of operations of the machine, and means thrown into operation on stopping the machine and operating during the reverse rotation of the cam shaft to unlock 25 the work rest and work guide and retract the work guide.

LAURENCE E. TOPHAM.
